[57] CLAIM

The ornamental design for ski pole with ergonomic grip, as shown and described.

DESCRIPTION

FIG. 1 is a perspective view of the right-hand ski pole of this design.

FIG. 2 is a left side elevational view of the right-hand ski pole.

FIG. 3 is a top plan view thereof.

FIG. 4 is a bottom plan view thereof.

FIG. 5 is a rear elevational view of the ski pole of this design.

FIG. 6 is a front elevational view of the right-hand ski pole of this design; and,

FIG. 7 is a right side elevational view of the right-hand ski pole of this design.

The left-hand ski pole of this design is a mirror image of the right-hand ski pole depicted.

The basket or snow ring of the ski pole is shown in dashed lines as its exact configuration forms no part of this design.
